UNITED STATES PATENT OFFICE.

WALTER W. LEWIS AND JOHN R. SUMAN, OF HOUSTON, TEXAS.

CEMENT-DUMPING BUCKET.

Application filed August 3, 1926. Serial No. 126,895.

Our invention relates to an improvement in dumping valves to be employed in cement buckets and similar devices employed in oil well operations. In cementing wells, it is 5 more or less common to place the cement in a bucket which is lowered to the bottom of the well and the cement discharged from the bucket at the desired point. The discharge means includes a valve at the lower 10 end of the bucket which has a projecting dart which contacts with the bottom of the well and raises the valve from its seat, allowing the cement to discharge. The difficulty with this arrangement is that the valve 15 is too easily unseated while going into the well, with the result that leakage very often occurs so that the full charge of cement is not delivered at the bottom of the well where desired.

20 It is an object of our invention to provide an attachment for the valve in a cement bucket whereby the valve will be retained in its seat until the bottom of the well is reached, allowing the valve to be again seated without difficulty before the bucket is again used.

25 Referring to the drawing herewith, we have illustrated one embodiment of the invention, Fig. 1 being a side elevation of one 30 form of cement bucket having our improved valve thereon. Fig. 2 is a central vertical section of the lower end of the bucket showing the valve in position therein. Like numerals of reference designate like parts in 35 both views.

In the drawing, I have shown a bucket 1, such as may be employed for holding cement while it is lowered to the bottom of the well. Said bucket has an upper bail 2 40 which may be engaged by a cable or other flexible device for lowering the same into the well.

At the lower end of the bucket is a valve 45 housing 3 threaded at its upper end for attachment within the lower end of the bucket. The valve housing is tubular in shape, having a central passage 4 therethrough to allow an outlet for the cement. The upper end of the housing is formed with a rounded seat 5 to receive a valve 6.

The valve 6 comprises a cylindrical head, the lower end of which is rounded to fit the seat 5. A valve stem 7 extends centrally 50 downwardly through the opening 4 and has projecting from the lower end of the housing 55 a dart 8. This is a flattened member

adapted to contact with the bottom of the hole when the bucket is used.

In order to prevent the upward movement of the valve while the bucket is being lowered, we provide on opposite sides of the valve stem 7 and spaced downwardly from the upper end thereof a pair of spring members 9. These springs are somewhat narrow and flattened plates, the upper ends of which 60 are provided with openings to receive a pin or bolt 10 extending diametrically through the valve stem 7 and acting to clamp the upper ends of the spring members 9 within shallow recesses 11, formed in the sides of the said valve stem. The plates are curved 65 outwardly at their lower ends to fit against the inner walls of the passage 4. One of these springs 9 is shorter than the opposite spring 9' so that the ends of the two springs 70 may engage within a spiral groove or recess 12 in the inner wall of the housing. This groove 12 forms a thread on the interior of the housing and, as the ends of the two springs engage within the troughs 75 of the thread, the rotation of the valve will allow the movement of the spring and the valve stem downwardly when necessity arises.

In the operation of the device, the valve 80 is seated at the lower end of the bucket and in so doing it may be necessary to rotate the valve stem, pulling downwardly during said rotation upon the lower end of the valve. The bucket is then ready for use, and when it 85 is lowered into the well to the bottom thereof, the lower end 8 will strike the bottom, forcing the valve up off its seat and allowing the discharge of the cement through the passage 4 about the valve stem. It will be 90 noted that the springs bearing in the troughs of the groove or thread 12 will tend to resist any accidental blow upon the valve tending to unseat the same and will also prevent the valve from falling off its seat due to pressure of liquid below it. The heavy blow received at the lower end of the valve when it strikes the bottom of the well will, however, unseat the valve in the usual manner.

The bucket will then be raised to the surface 105 and the valve again seated by drawing downwardly on the lower end 8 of the valve and rotating it in the proper direction to move the valve stem and the springs downwardly with a screw motion, in an obvious 110 manner.

The bucket may be used for other pur-

poses than the dumping of cement. It is also contemplated employing it to discharge a bucket of water at the bottom of the well in standard drilling operations and it is 5 obvious that it has many uses of a similar nature.

The use of this type of valve will effectively prevent the usual difficulties with a valve of this kind but will not prevent the ready 10 seating of the valve before the bucket is again filled. It is simple and substantial in construction and economical to manufacture.

Having thus described our invention, what we claim as new and desire to protect 15 by Letters Patent is:

1. In a cement bucket or the like a valve housing at the lower end thereof having a tubular passage therethrough, a valve at the 20 upper end of said housing, a valve stem thereon projecting downwardly through said passage, said passage having a spiral groove cut upon the interior thereof and springs on said valve stem engaging said groove, in the manner described.
2. In a cement bucket or the like, a valve housing at the lower end thereof having an axial passage therethrough, a valve in said 25 bucket to close said passage, a stem on said valve projecting downwardly through said passage, and means on said valve stem engaging within said passage to resist the

movement of said valve from said passage, and adapted to permit seating of said valve only by rotation of said stem relative to said housing.

35

3. In a cement bucket or the like, a valve housing at the lower end thereof having an axial passage therethrough, said passage having a spiral groove therein, a valve in said bucket to close said passage, a stem on 40 said valve projecting downwardly through said passage, and means on said valve engaging within said passage to resist the movement of said valve from said passage comprising springs on said stem projecting into 45 said groove.

4. In a device of the character described a bucket, a valve housing at the lower end thereof having a passage longitudinally thereof, a valve at the upper end of said 50 passages, a stem on said valve projecting downwardly through said passage, opposite springs on said stem engaging said passage, one spring being longer than the other to fit within a spiral groove in said passage, and 55 allow said stem to be screwed from said passage.

In testimony whereof we hereunto affix our signatures this 30th day of July, A. D. 1926.

WALTER W. LEWIS
JOHN R. SUMAN.
